CLAIM

The ornamental design for a band-blade bender for a band-blade bending machine, as shown and described.

DESCRIPTION

FIG. 1 is a front elevational view of a band-blade bender for a band-blade bending machine showing my new design;

FIG. 2 is a rear elevational view thereof;

FIG. 3 is a right side elevational view thereof, the left side elevational view being a mirror image;

FIG. 4 is a top plan view thereof;

FIG. 5 is a bottom plan view thereof; and,

FIG. 6 is a rear, top and right side perspective view thereof.
